UNITED STATES PATENT OFFICE.

JOCELYN EMILE OLLIVIER, OF LA VIGNETTE ST.-GERVAIS, FRANCE.

DRIVING DEVICE FOR AUTOSLEDS.

Application filed May 19, 1920. Serial No. 382,599.

To all whom it may concern:

Be it known that I, JOCELYN EMILE OLLIVIER, residing at La Vignette St.-Gervais, Department of the Haute-Savoie, France, **6** have invented certain new and useful Improvements in Driving Devices for Autosleds, of which the following is a specification.

This invention relates to an automobile sled and the driving means therefor, and more particularly to a non-slipping driving wheel having doubly-pivoted spikes, as set forth in Patent No. 1,225,999 dated May 15, 1917, in which the wheel is provided with **15** links or rods pivoted thereupon, arms pivoted to the said links, and spikes disposed upon the outer ends of the said arms and adapted to assume a swinging movement, the links or rods being preferably mounted **20** so as to pivot not directly upon the wheel, but upon annular rings secured thereto.

My invention has as its object to provide different means for obtaining a demountable assembling of the annular rings with the **25** wheel, for the purpose of affording a more rapid and convenient mounting and demounting of the said rings and of the entire assemblage of the non-slipping teeth.

The accompanying drawings represent by **30** way of example a number of practical embodiments of this invention.

In Figs. 1 and 2, the annular rings upon which the spikes D are mounted by means of the double pivoted links, are each composed **35** to two semi-circular rings 1 and 1' having a right angled section. These rings are assembled with the four rods 2 by means of the straps 3 which are bolted upon one flange of the ring and thus clasp the journaled portion **40** formed on each end of the rods 2 and having a shoulder on either side thereof. The said rods are secured to the wheel in the following manner. Each rod 2 contains two journaled portions 4 upon its ends, which are **45** adapted to rotate within the straps 3, and a portion 5 of square or hexagonal form adapted to be operated by means of a wrench or other suitable device, as well as two portions 6, 6', screw-threaded in contrary sense **50** and having disposed thereon the jaws 7, 7' in the form of nuts. Fig. 8 represents a front elevational view of a jaw member of this kind. By using a wrench upon

the portion 2 to effect the rotation of the rod 2 the jaws 7, 7' are brought together or separated in order to clamp the edges of the felly or to separate the jaws therefrom, for the purpose of mounting the rod 2 upon the felly or demounting the same, and consequently the said annular **55** rings together with their assemblage of pivoted spikes.

Fig. 3 and also Fig. 4 which is a sectional view along the line IV—IV (Fig. 3), represent an alternative form as concerns the **60** stop or abutment portion of the link 9 which contains pivoted upon one end thereof the corresponding arm of the spike D. The said link is provided with the projection 10 adapted to strike against one flange of the **65** angle member constituting the ring 1, thus preventing the link 9 from swinging clockwise of the approximately radial line passing through the center of the wheel, as shown in Fig. 3. The two studs provided with the **70** shoulders 11 and 12 are assembled respectively by riveting and by screw thread and nut, upon the arm 8 of the spike and upon one flange of the angle iron annular ring, **75** 1, constitute pivots for the link 9. An alternative form is represented in Fig. 15 and in Fig. 16 which is a sectional view along the line XVI—XVI (Fig. 15), the projection **80** 10 of the link 9 being shaped as represented in Fig. 16, for the purpose of striking **85** against the rim of one flange of the angle member 1.

Figs. 5, 6 and 7 represent another method of mounting the annular rings. In this case the rings have a T section and are assembled **90** with the rods 2 by means of the nuts 13, 13' screwed upon the threaded ends 14, 14' of the rod 2, these ends having a smaller diameter than the main part of the rod and being adapted to fit into suitable slots 15, 15' in **95** the respective annular rings. For the purpose of holding the two semi-circular rings 1, 1', tightly and securely upon the rod 2 which is located at the joint, the arrangement shown in Fig. 7 can be employed. Each of **100** the semi-circular rings 1, 1' carries two small cylindrical studs 16, 16' riveted to the corresponding ring 1, 1'; a plate 17 having two holes corresponding to the studs 16, 16' is placed upon the two studs which enter the **105** respective holes therein; the plate is also

provided with a central hole adapted to receive the end 14 of the rod 2, and the entire assemblage of these members is held in place by means of the nut 13 screwed upon the 5 threaded end 14.

Figs. 9 and 10 show another method of mounting the annular rings in which they are clamped to the felly by means of the jaws 7, 7'. In this arrangement, the jaws 7, 7' 10 are provided with the flat projections 25 upon which are assembled by means of the bolts 18, the semi-circular rings 1, 1', these latter having an angle section in the present case.

Fig. 11 represents a method in which each 15 of the semi-circular rings 1 or 1' is itself composed of two half members 26, 27 pivoted to each other by the pin 28. To each of the said members in the shape of a quarter circle 26 and 27 is secured respectively the 20 half jaw 29, 30, and on pivoting the said members about the pin 28 in order to bring them for instance into the position represented by the dotted lines 26', 27', the halves of the jaw 29, 30 will separate from 25 each other and release the end of the rod 2. The ends of the semi-circular ring thus formed are secured to the wheel by means of straps and bolts, as shown in Fig. 2.

Fig. 12 represents the annular rings 30 mounted and folded up, whereby the space occupied by the same will be reduced.

In Figs. 15 and 16 is shown an alternative form of the construction represented in Fig. 1. In this form, each of the pivot rods 2 35 is made hollow and is traversed by a bolt 32 having the head 32' and nut 34, for the purpose of securing the angle pieces 31 containing pivoted thereto the links 9 of the spikes; the small plates 33 are attached to 40 the members 31 opposite the rods 2, and these plates are provided with slots into which is inserted the bolt 32. Screwing the nut 34 upon the threaded end of the bolt will effect the tightening of the plates 33 against the 45 shoulder 35 on the end of the hollow rod 2, and this provides for the clamping of the angle members 31 with reference to the said rods 2.

In Fig. 17, the head 32' of the bolt 32 50 is provided with a spur 36 adapted to enter one of the corresponding holes provided in the plate 33 and the angle piece 31.

In Fig. 18, the points of junction of the angle members 1, 1', are located in the space 55 between two adjacent shafts or rods 2, and in order to provide a very reliable assembling, one of the members 1 carries two small studs 37 adapted to enter corresponding holes in two small lugs 38 which are mounted upon 60 the second member 1'.

Claims.

1. A traction device adapted to be mounted upon a wheel comprising two cheek members adapted to be positioned on opposite 65 sides of a wheel, anti-slipping means con-

nected to said cheek members and uniting said members, pairs of jaws adapted to be disposed on opposite sides of a wheel felly, means detachably connecting the jaws to said cheek members, and means for drawing 70 the jaws of each pair together to clamp the sides of a wheel felly.

2. A traction device adapted to be mounted upon a wheel comprising two cheek members adapted to be positioned on opposite 75 sides of a wheel, anti-slipping means adapted to extend across a wheel tread and pivotally connected to said cheek members, said means joining the cheek members, pairs of jaws adapted to be disposed upon opposite sides 80 of a wheel felly, means for detachably connecting the jaws to said cheek members, and means for moving the jaws together independently of the cheek members for clamping 85 the sides of a wheel felly.

3. A traction device adapted to be mounted upon a wheel comprising a pair of jaws, the jaws adapted to be disposed upon opposite sides of a wheel and to grip the latter, a rod having reversely threaded portions 90 engaging the jaws and adapted to draw them together to grip a wheel, members supported by the jaws at each side of the wheel, and anti-slipping means pivotally connected to 95 said members.

4. A traction device adapted to be mounted upon a wheel comprising a pair of jaws, the jaws adapted to be disposed upon opposite sides of a wheel and to grip the latter, 100 a rod having reversely threaded portions engaging the jaws and adapted to draw them together to grip a wheel, an annular member supported by the jaws at each side of the wheel and removably connected to said rod, and anti-slipping means pivotally connected 105 to said annular members.

5. A traction device adapted to be applied to a wheel comprising a pair of jaws for gripping each side of the wheel, a reversely threaded rod for drawing together 110 the jaws, an annular member disposed at one side of the wheel and removably connected to said rod to be supported by the jaws, and anti-slipping means removably connected to said annular member.

6. A traction device adapted to be mounted upon a wheel comprising two rings adapted to be mounted upon opposite sides of a wheel, each ring being formed of two semi-circular portions, anti-slipping means pivotally connected to said rings, and means for supporting said rings upon the wheel comprising a pair of jaws adapted to grip the wheel upon its opposite sides, and a reversely threaded rod, to which said rings are removably connected, adapted to draw together 120 said jaws.

7. A traction device adapted to be mounted upon a wheel comprising rings disposed on opposite sides of the wheel, anti-slipping 125

members secured to said rings, and means for supporting said rings upon a wheel comprising a pair of jaws adapted to grip the opposite sides of a wheel, a hollow rod having threaded portions and adapted to draw together said jaws, and a bolt passing through said rod, said rings being connected to said bolt.

8. A traction device adapted to be mounted upon a wheel comprising rings disposed upon opposite sides of the wheel, anti-slipping means pivotally connected to said rings, and means for supporting said rings upon the wheel comprising a pair of jaws adapted to grip the wheel upon its opposite sides, a hollow rod having threaded portions and adapted to draw together said jaws, a bolt

passing through said rod, and means for securing the rings to said bolt.

9. A traction device adapted to be mounted upon a wheel comprising rings disposed upon opposite sides of the wheel, anti-slipping means pivotally connected to said rings, and means for supporting said rings upon the wheel comprising a pair of jaws adapted to grip the wheel upon its opposite sides, a hollow rod having threaded portions and adapted to draw together said jaws, a bolt passing through said rod, and plates secured to said rings extending inwardly therefrom and having openings to receive said bolts.

In testimony whereof, I have signed my name to this specification.

JOCELYN EMILE OLLIVIER.
